DESIGN.

J. KINGSBURY.
COUPELET SLEIGH.

No. 18,237.

Patented Apr. 3, 1888.

UNITED STATES PATENT OFFICE.

JOHN KINGSBURY, OF ALBANY, NEW YORK.

DESIGN FOR A COUPELET-SLEIGH.

SPECIFICATION forming part of Design No. 18,237, dated April 3, 1888.

Application filed December 6, 1887. Serial No. 257,168. Term of patent 7 years.

To all whom it may concern:

Be it known that I, JOHN KINGSBURY, of the city and county of Albany, in the State of New York, have invented and produced a new and original Design for a Coupelet-Sleigh, of which the following is a full and exact description, reference being had to the accompanying photographic illustrations, which are herein referred to and form part of this specification, and in which—

Figure 1 is a perspective view of my coupelet-sleigh with the top frame raised for the purpose of showing the panels in the front of the body, and Fig. 2 is a like view with the top frame turned down.

Heretofore barouche-sleighs and landaulet-sleighs have been produced for filling during the sleighing season the place of wheeled vehicles bearing similar designations which are designed for use in warmer seasons or in warmer climates; but so far as my knowledge extends no sleigh has heretofore been produced to occupy the same relation to the wheeled vehicle that is known as a "coupelet."

The leading features of my present design consist, first, in the body of the sleigh, which presents the distinctive character of a coupelet, the forward end of the main body terminating in close proximity to the forward side of the door-opening with a coupé-pillar, and the forward extension, which has nearly the same width that is given to the main body, having a lower outline that is substantially a continuation of the sweep of the "rocker" or sunken bottom of the main body; and, second, of the ornamental scroll-work which is interposed between the upper line of the runners and lower line of the main body, as shown in the illustrations and described herein.

As represented in the illustrations, A designates the runners of my sleigh, which at their forward part are curved upwardly and then continued in an approximately straight line to their upper ends, which terminate in an ornamental head, 1. The rearmost ends of said runners have on their lower side an upward convex curve, 2, which conforms to the sweep of the rearward terminal of the ornamental scroll-work hereinafter described.

B designates the main body of my coupelet-sleigh, the sides of which have the outward

swell usually given to sleigh bodies. The rearmost end of said main body has a convex outline, 3, which extends upwardly from an obtuse point, 4, that is formed by the joining of said line to another convex outline, 5, which as it is carried forward and downward is merged into a flatter curve, 6, that extends to the forward end of said main body, where at the point 7 it joins a concave line, 8, that is carried upward and is merged into an approximately-straight vertical line, 9, that is carried upward to the top of the main body, thereby forming in effect a coupé-pillar, b, at that part of said main body. The lower quarter-panel, C, is bordered on its lower side by a ravel molding, c, which is of a uniform width and follows the contour of the lower edge of the side of the main body, as defined by the convex outlines 5 and 6. The upper outline of said quarter-panel is defined by the lower edge of the belt D, which, meeting the ravel molding c at the point 4, forms a pointed terminal, 10, at the rearmost end of said quarter-panel. The belt D extends from the rearmost to the foremost edge of the main body, and at the latter point it joins to the molding c', which follows the concave outline 8 and imparts its form to the forward end of said quarter-panel. The belt D is about uniform in width throughout its length, and it follows a curvature that is substantially a compass sweep. The upper quarter-panel, E, and door-panel E' have their lower outline defined by the upper edge of the belt D, and their upper outline is defined by an approximately-straight horizontal line, 11, which extends across the side of the main body.

The door F has near its upper end a crest-panel or monogram-panel, 12, which preferably is of a rectangular form.

The forward extension, G, which includes the rocker H, begins at the under side of the after part of the main body B with a concave outline, 13, which sweeps downward and forward from the convex outline 5 at the rear end of the main body. The concave outline 13 forms an obtuse angle, 14, with a convex outline, 15, which extends forward nearly parallel with the curvature of the line 6 at the lower edge of the main body until a point nearly under the middle of the door F is reached, at

which point said outline is merged into a quicker convex outline, 16, which joins to the point 7, and is then carried forward to be merged into a concave outline, 17, which joins 5 to a horizontal line, 18, that underlies the dickey-seat I. Said horizontal line joins to an upwardly-inclined line, 19, that forms the lower outline of the bracket or foot-board J. Beginning at the forward end of the main body, 10 the forward extension, G, which is integral with said main body, has the following-named upper outline: A concave outline, 20, bordered by a narrow half-round bead or molding, 21, sweeps upwardly to join a horizontal line, 22, on which the dickey or driver's seat I is placed. From the forward side of the latter a concave outline, 23, sweeps downward to join an upwardly-inclined outline, 24, which forms the upper edge of the bracket J. The 15 paneled dash-board L is at the forward end of the bracket J; but as said dash-board is fully described in the Design Patent No. 17,631, granted to me August 16, 1887, further description is deemed unnecessary. The front M of the main body has an arched molding, 25, across it, and 20 above the latter a straight molding, 26, is arranged. The moldings 25 and 26 join the vertical edge moldings 27 to produce the sunken panels m and m'. A window-panel, N, is 25 formed in the upper portion of said front.

An ornamental scroll, O, is interposed between the lower line of the main body and the upper line of the lower portion of the runners A, and said scroll extends from near the forward end of each runner to the rear end of the same. Said scroll-work consists of the following parts: An open circle, 28, which reaches from the upper side of the runner A to the under side of the forward extension, G, joining 30 to the latter at the line 18 under the dickey-seat I. From said circle a scroll, 29, extends forward to join the vertical part of the runner, and is then turned back to the under side of the bracket J. Another scroll, 30, extends from the after side of the circle 28, and, after being carried upward and rearward to join the lower side of the rocker H, forms a downward-curved scroll, 31, which joins to the upper side of the runner A. Next in succession is a scroll, 32, which extends upward and rearward from the scroll 31, and, after joining the under side of the rocker H, is curved downward to form a scroll, 33, which joins the upper side of the runner A. The upper end of 35 the rearmost scroll, 34, joins the after side of the main body at the convex outline 5, then curving downward it joins the scroll 33 at 35, from which it curves downward and rearward to join the upper side of the runner A, and is 40 then coiled to form a terminal scroll, 36, which conforms to the curvature of the convex outline 2 at the rear end of the runner A.

What I claim as new, and desire to secure by Letters Patent, is—

1. In a design for a coupelet-sleigh herein 65 described and shown, the shape and configuration of the main body B and forward extension, G, the first being defined by the convex lines 3, 5, and 6, concave line 8, vertical line 9, and horizontal line 11, and the other being 70 defined by the concave lines 13, 17, 20, and 23, convex lines 15 and 16, horizontal lines 18 and 22, inclined lines 19 and 24, and dickey-seat I, as herein specified.

2. In a design for a coupelet-sleigh herein 75 described and shown, the ornamentation of the sides of the main body B, consisting of a lower quarter-panel, C, as defined by the ravel molding c, forward molding, c', and lower convex line of the belt, the parallel belt D, as defined 80 by the upper concave line of the lower quarter-panel and lower convex line of the upper quarter-panel, and the upper quarter-panel, E, and door-panel E', as defined by the upper concave line of the belt D and the horizontal 85 line 11, as herein specified.

3. In a design for a coupelet-sleigh herein 90 described and shown, the shape and configuration of the forward extension, G, and rocker H, whose upper outline is defined by the curved lines of the lower edge and front of the main body B, concave lines 20 and 23, horizontal line 22, and inclined line 24, and whose lower outline is defined by the concave lines 13 and 17, convex lines 15 and 16, and 95 inclined line 19, as herein specified.

4. In a design for a coupelet-sleigh herein 100 described and shown, the ornamentation of the front M of the main body, consisting of the arched molding 25, transverse molding 26, edge-moldings 27, sunken panels m and m', and window-panel N, as herein specified.

5. In a design for a coupelet-sleigh herein 105 described and shown, the shape and configuration of the scroll-work O, composed of an open circle, 28, scrolls 29, 30, 31, 32, 33, and 34, and terminal scroll 36, as herein specified.

6. In a design for a coupelet-sleigh herein 110 described and shown, the shape and configuration of the main body, forward extension, and scroll-work, said main body being defined by the convex lines 3, 5, and 6, concave line 8, vertical line 9, and horizontal line 11, said forward extension by the concave lines 13, 17, 20, and 23, convex lines 15 and 16, horizontal 115 lines 18 and 22, inclined lines 19 and 24, and dickey-seat I, and said scroll-work by the open circle 28, scrolls 29, 30, 31, 32, 33, and 34, and terminal scroll 36, as herein specified.

JOHN KINGSBURY.
